UNITED STATES PATENT OFFICE.

ADAM HEIM, OF BROWNSVILLE, INDIANA, ASSIGNOR OF ONE-HALF TO
CHARLES A. RIEMAN, OF CONNERSVILLE, INDIANA.

FLOWER-SUPPORTER.

No. 827,442.

Specification of Letters Patent.

Patented July 31, 1906.

Application filed December 8, 1905. Serial No. 290,872.

To all whom it may concern:

Be it known that I, ADAM HEIM, a citizen of the United States, residing at Brownsville, Indiana, have invented a new and useful Improvement in Flower-Supporters, of which the following is a specification.

My invention relates to flower-supporters of the class adapted to the use of floriculturists or others in maintaining carnations or other flowers in an upright position during the period of their growth or at other times; and the objects of my improvement are to provide a standard consisting of a double wire and preferably formed with one or more intermediate twists to prevent its torsional movement and secure greater rigidity, which may be secured in the soil of the flower-bed, and to provide a series of horizontal rings removably and adjustably secured on the standard to encircle the flower-stock at different elevations to support it in an upright position, to form the rings either single or in pairs and of different sizes adapted to the same standard whereby it may be utilized for one or more large or small plants, as desired. These objects are attained in the following-described manner, as illustrated in the accompanying drawings, in which—

Figure 1 is a perspective view of a flower-supporter embodying my improvement and provided with a series of pairs of rings; Fig. 2, an enlarged front elevation with parts broken away; Fig. 3, a plan with parts in section on the line *a a* of Fig. 2 with portions broken away; Fig. 4, a perspective view of a supporter provided with a series of single rings, and Fig. 5 an enlarged front elevation of parts thereof.

In the drawings, 6 represents the standard, which consists of a single wire doubled by a central bend 7 to form parallel sides 8 and 9, which are extended a sufficient distance and terminate in being twisted together at 11. The ends of the wire are extended from said twist in opposite directions perpendicular to the plane of the sides and by means of bends 12 terminate in feet 13, parallel with and on opposite sides of the extended plane of the standard. The said sides may be twisted together at one or more intermediate points 14 to increase the rigidity of the standard and prevent any torsional or twisting motion thereof. Pairs of supporting-rings 15 and 16 of any desired sizes are formed in the same

plane by circular bends in a single piece of 55 wire on opposite ends of its straight middle portion which forms a connecting cross-bar 17 between them and in the line of their centers of sufficient length to extend across and a short distance beyond the sides of the 60 standard. The rings are closed by turns 18 being formed in the wire around the ends of the cross-bar and the extremities of the wire terminate therefrom in helices 19 perpendicular to the plane of the rings. Said helices are formed with open coils to adapt them 65 to be detachably engaged with the respective sides of the standard, whereon they are also longitudinally adjustable. The rings are extended in opposite directions from the 70 edges of the standard instead of from opposite sides of its plan to adapt them to register with flowers planted farther apart.

Should it be desirable to provide the supporting-rings singly instead of in pairs, one of 75 the rings may be replaced by a helix 19, formed directly on one end of the cross-bar 17, as shown in Figs. 4 and 5.

In operation one or more of either the pairs of rings or single rings, proportioned 80 in size as desired, may be detachably engaged, by means of the helices thereon, with the standard. The standard may be maintained in a vertical position by inserting its feet in the soil of the flower-bed with the 85 flowers on opposite sides of the plane of the feet and in a line with the axis of a corresponding series of superposed rings to prevent the feet from injuring the roots of the flowers. The rings may be adjusted in different positions of elevation on the standard, 90 as desired, to properly support the flower in closed therein. The rigidity of the supporter protects the flower within the rings from being accidentally broken and also 95 facilitates the cutting of the flowers without injury to the stalk.

Having fully described my improvement, what I claim as my invention, and desire to secure by Letters Patent of the United States, 100 is—

1. In a flower-supporter, the combination with a single standard consisting of a wire doubled to form parallel sides, and twisted together at an intermediate point of the sides, 105 and also near one end thereof, said wire being extended in opposite directions from said latter twist perpendicular to the plane of the

sides and terminating in feet parallel with each other, of a wire ring adapted to be detachably engaged with said standard on either side of said intermediate twist and 5 adjustably supported thereon with the center of said ring in the extended plane of the sides.

2. The combination with a standard consisting of a wire doubled to form parallel sides 10 and twisted together near its ends, of a ring provided with open-coiled helices perpendicular to its extended plane, said helices being adapted to detachably engage with intermediate portions of the respective sides.

15 3. The combination with a standard consisting of a wire doubled to form parallel sides and twisted together near its ends, of a wire ring provided with a bar in the line of its radius, and with open-coiled helices extending 20 from said bar perpendicular to the plane of the ring, said helices being adapted to detachably engage with intermediate portions of the respective sides.

4. The combination with a doubled-wire 25 standard formed with parallel sides and twisted together near its ends, of a wire ring provided with open-coiled helices perpen-

dicular to its plane and in the line of its radius, said helices being adapted to detachably engage with intermediate portions of the respective sides and adjustably support the ring thereon with its center in the extended plane of the standard. 30

5. In a flower-supporter, the combination of a standard formed with parallel sides connected together at an intermediate point, and a pair of closed rings connected together by a cross-bar and formed with helices at the ends thereof perpendicular to the common plane of the rings, said helices being formed with 40 open coils adapted to be detachably engaged with the respective sides of the standard between the points of connection thereof. 35

6. In a flower-supporter, the combination of a doubled-wire standard, and a pair of wire 45 rings formed in the same plane, said rings being provided with open-coiled helices adapted to be detachably and adjustably engaged with an intermediate portion of the standard.

ADAM HEIM.
